Attorney.

UNITED STATES PATENT OFFICE.

CHARLES CRETORS, OF CHICAGO, ILLINOIS.

EXTENSIBLE WAGON-AWNING.

SPECIFICATION forming part of Letters Patent No. 788,755, dated May 2, 1905.

Application filed March 5, 1904. Serial No. 196,770.

To all whom it may concern:

Be it known that I, CHARLES CRETORS, a citizen of the United States of America, and a resident of Chicago, in the county of Cook 5 and State of Illinois, have invented certain new and useful Improvements in Extensible Wagon-Awnings, of which the following is a specification.

This invention relates to awnings for wagons employed in retailing commodities in cities, and has for its object to provide a simple, durable, and convenient awning for such use and which is capable of ready extension to afford the desired protection at the side and rear end of the wagon, all as will hereinafter more fully appear and be more particularly pointed out in the claims.

In the accompanying drawings, illustrative of the present invention, Figure 1 is a side elevation of the awning-frame of a wagon embodying the present invention. Fig. 2 is a plan view of the same with the extensions shown as extended in dotted lines. Fig. 3 is an end elevation.

Similar numerals of reference indicate like parts in the several views.

Referring to the drawings, 1 represents the framing of an ordinary wagon-awning, supported at the proper elevation above the wagon-body by posts or other like support 2, and which framing will usually consist of a horizontal rectangular frame 3, braced together at the corners by diagonal braces 4 and provided with inclined rafters 5, carrying 35 a central ridge-pole 6, to form a roof-like support for the canvas which constitutes the stationary awning or roof of the wagon.

7 is the driver's hood, extending forward from the main frame 1, over the driver's seat, 40 and formed by a skeleton framing of any usual form and covered with canvas in like manner to the main frame 1.

The present invention involves the combination, with the above type of wagon roofs or awnings, of an auxiliary extensible attachment which is capable of being drawn out at the rear end and at one side of the wagon to protect the vendor and purchaser of the articles or commodities from the wagon, and 45 which auxiliary awning is capable of being

closed against the main awning when not required and with a view to avoid interference in hauling the wagon from place to place. To such end the present improvement comprises a structural formation of parts as follows: 8 55 is a longitudinal rail provided at its ends with right-angle guide rods or members 9, sliding in guides 10 on the main awning-frame 1, so as to admit of the aforesaid rail 8 being pushed up close to the main awning-frame or drawn 60 away from the same the required distance and in parallel relation to said main frame. In the preferred form of the present invention as shown in the drawings, the guide-rods 9 and the guides 10 therefor will be arranged 65 in an inclined direction from a horizontal in order that the auxiliary frame extended—the canvas covering thereof which extends from a marginal rail of the main awning-frame to the longitudinal rail 8 of the auxiliary frame—70 will have a corresponding downward inclination to shed rain in wet weather.

11 represents set-screws or other equivalent clamping means engaging the guide-rods 9 to fasten the same at any desired adjustment 75 of the auxiliary awning-frame of which they form a part.

12 is a rail arranged transversely of the wagon and at the rear end of the same. Such rail is provided at its ends with horizontal 80 guide rods or members 13, arranged to move in guides 14 on the main frame, and as so arranged the rail 12 is adapted to be pushed up close to the end of the main awning-frame 1 out of the way or drawn out so as to extend 85 the usual canvas covering connected to the rail 12 and to the end rail of the main awning-frame to afford protection to a person standing at the end of the wagon.

15 represents set-screws or like clamping 90 means engaging the guide-rods 13 to fasten the same at any desired adjustment of the transverse rail 12 aforesaid.

Having thus fully described my said invention, what I claim as new, and desire to secure 95 by Letters Patent, is—

1. An extension-awning for wagons, comprising in combination a main awning-frame, posts supporting the same above the wagon-body, a skeleton auxiliary awning-frame com- 100

- prising a longitudinal outer rail and a pair of guide-rails attached at right angles to the ends of the aforesaid longitudinal rail, and guide-eyes on the under side of the main awning-frame and in engagement with the guide-rails aforesaid to impose a rectilinear movement upon the auxiliary awning-frame in a substantially horizontal plane substantially as set forth.
- 10 2. An extension-awning for wagons, comprising in combination a main awning-frame, posts supporting the same above the wagon-body, a skeleton auxiliary awning-frame comprising a longitudinal outer rail and a pair of

guide-rails attached at right angles to the ends 15 of the aforesaid longitudinal rail, and guide-eyes arranged in an inclined direction on the under side of the main awning-frame and in engagement with the guide-rails aforesaid to impose rectilinear movement upon the auxiliary awning-frame in a direction inclined from a horizontal, substantially as set forth. 20

Signed at Chicago, Illinois, this 3d day of March, 1904.

CHARLES CRETORS.
